UNITED STATES PATENT OFFICE

ALFRED M. GOODLOE, OF BRADFORD, PENNSYLVANIA, ASSIGNOR, BY MESNE ASSIGNMENTS, TO AMERICAN AIR FILTER COMPANY, INC., OF LOUISVILLE, KENTUCKY, A CORPORATION OF DELAWARE

HUMIDIFIER

Application filed December 3, 1927. Serial No. 237,515.

My invention relates to improvements in ported by means of any convenient part of humidifiers, particularly to humidifiers for the structure in which the humidifier is to be employed; for example, a channel beam imparting moisture to the atmosphere in manufacturing plants and in other establish- indicated on the drawings at 8.

5 An object of the invention is to provide a humidifier which can be automatically cleaned and prevented from becoming ob- structed or clogged, especially at the dis- charge nozzles thereof.

10 A further object of the invention is to pro- vide a humidifier that is of simple construc- tion, easy to mount and economical, efficient and certain in operation.

15 Other objects and advantages of the in- vention are set forth in the following de- scription, taken with the drawings, on which a preferred form of my invention is pre- sented. But the disclosure is illustrated 20 only, and I reserve the right to make changes in shape, size and arrangement of parts that are within the principle of the invention and embraced by the broad meanings of the terms in which the appended claims are expressed.

25 On the drawings—

Figure 1 is a side view of a humidifier ac- cording to my invention;

Fig. 2 is a front view thereof;

Fig. 3 is a top view;

30 Fig. 4 is a section on the line 4—4 of Fig. 1;

Fig. 5 is a section taken on the line 5—5 of Fig. 3, and

35 Fig. 6 is a detailed view showing a mod- ification.

The same numerals identify the same parts throughout.

In the detail description of what the drawings show, I use the numeral 1 to indicate a spray nozzle for water and 2, an air nozzle. The discharge or delivery ends of these nozzles are disposed in proximity to each other, as indicated in Fig. 5 and are located within a hood 3 having an outlet opening 4 in line with the discharge ends of the nozzles 1 and 2. The nozzle 1 is supplied with water through a pipe or conduit 5, and the air nozzle 2 is connected to an air pipe or con- duct 6. The entire construction is attached to a mounting plate 7 which can be sup-

55 In previous humidifiers of this type, ex- perience has shown that the spray nozzles for the air and water are apt to become choked- up after a while and then they must be cleaned out to enable them to be kept in operation. Such cleaning is usually expensive and 60 troublesome; and to avoid the labor and loss of time entailed thereby, I provide the hu- midifier of this invention with means for automatically cleaning the nozzles 1 and 2 whenever the operation of the humidifier 65 ceases. When the humidifier is again needed for use, the efficient operation of same can at once be resumed. For this purpose, I pro- vide each of the spray nozzles 1 and 2 with a cleaning rod 25, the ends of which shown 70 at 26 and 28 project through the delivery ends of the nozzles; as best shown in Fig. 5; and these cleaning rods are connected with a piston 43 in an air cylinder 41; the piston and cylinder being best shown in Fig. 4. One 75 side of the piston 43 will be in communication with the air supply pipe 6, and the other side of the piston will be engaged by a helical spring 45; the spring normally operating as soon as the air supply is shut off to move the piston 43 in such a direction that the piston, 80 through suitable connections will actuate the rods 25 so that their ends 26 and 28 will be projected through the delivery ends of the nozzles 1 and 2 to push out any dirt or foreign 85 matter that may have lodged therein. After- wards, upon the humidifier being again put into operation, the turning-on of the air supply will move the piston in the opposite direction against the force of the spring 45, 90 so that the cleaning rods 25 will be with- drawn, opening the nozzles 1 and 2 and per- mitting them to discharge air and water again into the atmosphere to be treated. 95 This mode of action will be more fully set forth later.

The nozzles 1 and 2 may be produced in the form of a single casting so as to make them integral with each other, as indicated in Fig. 5; but, obviously a different construc- 100

tion may be adopted, if desired. The body or exterior casing of the nozzle 1 will have an extension 9, one end of which is threaded to be screwed into a piece of piping 10 to connect the nozzle 1 with the supply conduit 5. The bore 11 of this extension 9 communicates with the interior of the nozzle casing, and in the casing will be mounted a tubular member 12 surrounded by an annular space or chamber 13 to which the bore 11 leads. The member 12 may be designated as the nozzle proper and it will have threads 14 adjacent one end to engage with similar threads inside of the casing 1, so that the member 12 can be securely mounted in the casing 1. The washer 15 of leather or other material may encircle the member 12 at the end of the casing 1 where threads 14 are provided, and the threads 14 on this member 12 may be engaged by a threaded collar 16 and a lock nut 17 to hold the member 12 fast. As indicated in Fig. 5, the casing 1 which is in inclined position has threaded engagement with the member 12 adjacent its upper end; and at the opposite end of this casing the member 12 projects and is threaded to receive a similar washer 15, collar 16 and lock nut 17. The member 12 has a chamber 18 which communicates with the space 13 through ports 19 and the chamber 18 opens through the two ends of the member 12 by way of ducts 20. The end of the member 12 which projects from the lower end of the casing 1 has a recess or bore 21 in which is a packing of cork or the like 22 and a gland 23 having a head 24 to enable it to be engaged and turned by a tool. The gland 23 threads into the bore 21; and thus a stuffing box is provided through which projects leakproof the cleaning rod 25 for the water nozzle 1. The duct 20 at the opposite or delivery end of the nozzle 1, adjacent the outlet opening 4 of the hood 3, is reduced in size, so that it is no larger than the thin end 26 of the cleaning rod 25. This thin end 26 is connected to the body of the rod 25 by a conical shoulder 27 which fits against a conical seat inside of the member 12; and when the conical shoulder engages this seat, the thin end 26 of the cleaning rod projects beyond the delivery end of the nozzle and the discharge end of the nozzle 1 is therefore closed. To open the nozzle, the rod 25 must be pulled back so as to withdraw the end 26 from the relatively small outlet of the member 12 and then water can flow freely into the casing 1 by way of the bore 11, space 13, ports 19, chamber 18, duct 20 and out from the upper end of the nozzle, where the air from the nozzle 2 will atomize it and expel it through the opening 4 of the hood 3.

The inside construction of the complete nozzle 1 is illustrated fully in section on Fig. 5, while only the outside of the nozzle 2 is illustrated on the drawings. The parts on the inside of the nozzle 2, however, will be

the same as those on the inside of the nozzle 1, and the rod 25 will have a similar reduced or thin end shown at 28 to clean out the discharge end of the member 12 of this nozzle 2. In practice, I connect the cleaning rods 25 so that they can be operated in unison; so that these two cleaning rods can be moved to cause their ends 26 and 28 to project together out of the delivery ends of the members 12 of the two nozzles to clean same, or to be withdrawn and thus at the same time open the discharge ends of these parts and thus permit the two nozzles to deliver air and water in atomized condition when required.

The air supply pipe 6 is connected through a T-coupling 29 with a piece of tubing 30 and a pipe coupling 31 with the inside of the casing of the nozzle 2; and when the rod 25 of the nozzle 2 is withdrawn and air under pressure is in the pipe 6, this air will be issued through the discharge passage at the end of the nozzle 2 which has been evacuated by the extremity 28 of this rod 25 adjacent the outlet opening 4 of the hood 3. The piece of pipe or tubing 30 will be mounted in a bracket 32 having its upper end split as indicated at 33; the split portions having threaded openings to receive a screw 34 by which these split portions can be caused to grip the piece of tubing 30 and hold it in place. By loosening the screw 34, the piece of tubing can be adjusted or moved.

The top of the casing of the nozzle 2 may be provided with an integral projection 35 having a reduced extension 36 to form a journal for a rocker arm or lever 37. This arm can be held in place by a washer 38 and a cotter pin 39 passing through an opening in the journal 36. One end of this lever 37 has openings to receive the ends 40 of the two cleaning rods 25 which are bent as indicated by the drawings to engage the rocker arm 37 in this way. As will plainly appear from an inspection of Fig. 1, whenever the lever is operated to pull the two rods 25 to the left, the reduced extremities 26 and 28 of these two cleaning rods or elements 25 will be shot through the delivery ends of the members 12 or nozzles proper to clear out any obstruction therein; and when the lever is moved in the opposite direction, these rods will be withdrawn so as to open the ends of the members 12 and enable the humidifier to supply as much moisture as is needed.

The air cylinder 41 which controls the lever 37 can be cast in one piece with the mounting plate 7. It connects through its lower end with the air supply pipe 6 by way of an extension 42 of this pipe, so that when the air supply is turned on, the piston 43 tends to move upward against the force of the spring 45. The opposite or upper end of the cylinder 41 is closed by a head 44 provided with a bearing through which extends the piston rod 46 and the outer end of this piston rod is

slotted at 47 to receive the adjacent end of the lever 37 which is made fast by means of a pin 48. This pin passes through a slotted opening in the end of the arm 37 so that the piston 46 can properly actuate the lever 37.

5 In practice, the water and air are turned on to flow through the pipes 5 and 6. The spring 45 will keep the piston 43 down at the bottom of the air cylinder 41 and hold the lever 37 in such position that the reduced ends 10 26 and 28 of the cleaning rods 25 will extend out of the ends of the nozzles adjacent the opening 4, as indicated on Fig. 5. The turning on of the air, however, causes the piston 43 to move upward and the lever 37 is then 15 actuated to withdraw the cleaning rods 25. Air and water can then flow freely through the nozzles 2 and 1 respectively, and the water as soon as it is delivered by the nozzle 1, is broken up into a spray and blown out from 20 the hood 3 by the compressed air from the nozzle 2. Whenever the operation of the humidifier is stopped by cutting off the air and water, then the spring 45 causes the piston 43 to make the lever 37 move the rods 25 to 25 clean the two nozzles 1 and 2. Thus the humidifier is always maintained in condition for service and the humidifier never has to be shut down to be cleaned out; because no 30 dirt or the like can ever find a lodgement in the nozzles 1 and 2. Whenever the working of the humidifier is stopped, the nozzles are cleaned at once and the ends of the cleaning rods occupy the discharge ends of the nozzles 35 until the humidifier is again put in operation. Hence, on account of the discharge ducts of the nozzles 1 and 2 being always filled by the ends of the cleaning rods when these nozzles are not discharging, no dirt or foreign particles of any kind can lodge in the discharge 40 ends of the two nozzles and the nozzles can not possibly become clogged up.

The pipe line leading to the bottom of the cylinder 41 is provided with a pet cock 49 for draining and blowing-off purposes, and the bolts for securing the plate 7 to the support 45 8 are shown at 50. I may also make the bracket 32 adjustable with respect to the plate 7 by means of bolts 51 which may engage threaded openings in the plate 7, but pass 50 through slots 52 in the bracket 32, so that by loosening the bolts, the bracket can be raised or lowered, and then by tightening the bolts secured in the desired position.

55 This bracket may also have a perforated extension or bearing 53 to receive the piece of tubing 10, so that this connection between the extension 9 and supply conduit 5 may be securely mounted.

60 The hood 3 may have a projection 54 inside to engage a recess 55 in the top of the casing in the nozzle 2 and this hood may also carry a binding screw 56 to lock the hood in place over the ends of the nozzles 1 and 2.

65 This type of humidifier or atomizer can

be used in textile mills and other establishments by equipping each room with as many as are needed. In connection with each complete humidifier or unit, the full installation will include an air compressor with a motor to drive same, a controlling valve of the diaphragm type subject to the pressure of the compressed air for turning-on and shutting-off the water, and a one-way valve for regulating the flow of the water through the pipe 70 5, a humidostat, the necessary length of piping, and for large installations, a suitable relay to take care of the motor. When the humidity falls to some predetermined point, the humidostat will allow the compressor to start. As soon as the air compression rises to about 30 pounds per inch, the diaphragm valve will open the water supply conduit to allow water to flow to the atomizers as before. The one-way valve in the water conduit will 75 regulate the quantity of water that passes. Preferably the water is passed through the jacket of the compressor, having a cooling effect on the compressor and getting warmed 80 itself so that it can be atomized more quickly and humidify the air to better advantage. As the water line is opened, the pressure of air in the pipe 6 will actuate the piston 41 of each humidifier and cause the pulling back of 85 the cleaner rods 25. Air and water can now be emitted, so that water in the form of a fine spray is delivered from the hood 3. As soon as the humidity reaches a predetermined degree, the humidostat will cause the compressor to stop. When the compressor 90 ceases to run, the diaphragm valve will close the water line, and the spring 45 of each cylinder 41 will force down the piston 43 and the reduced ends 26 and 28 of the cleaner rods will again be projected through the discharge ends 95 of the nozzles 1 and 2. All necessary operations are thus mechanically performed, and the cleaning of each humidifier or unit is automatically and regularly accomplished.

The complete installation, of course, is not illustrated herewith for the reason that my invention resides in the construction of the humidifier itself, comprising two nozzles, the connections therefor and means for automatically cleaning the nozzles. From the foregoing description, it will be seen that nozzles are supported from the bracket 32 by means of the piece of tubing 30 and coupling 31 for the nozzle 2 and the bearing 53 receiving the section of piping 10 which joins the nozzle 1 to the conduit 5. The cylinder 41 is rigid with the plate 7, but the bracket 32 can be adjusted to make its position right for the proper connection of the cleaning elements 110 25 and the rod 46 with the rocker arm 47; and the connection between the T-coupling 29 and the cylinder 41 can then easily be made by taking pieces of piping of the right length 115 to provide the conduit 42. Of course, while air and water are usually delivered by the 120 130

nozzles 1 and 2, the nozzles might also be used to deliver any kind of gas or liquid if the liquid is to be converted into the form of a mist or spray.

5 The end 28 of the rod 25 in the nozzle 2 may be flattened, to deliver the compressed air in the form of a narrow sheet over the end of the nozzle.

10 In Figures 1 and 3 the piston 43 is illustrated in the position which it occupies when the air pressure forces it to move against the spring 45, to actuate the rocker arm 37 and withdraw the cleaning rods 25 from the water nozzle or air nozzle 2 so as to put these nozzles in condition for discharging. Figure 15 5 indicates the cleaning rods of these nozzles in the other position; that is, the rods are projected forward so as to occupy the discharge end of these nozzles when they are 20 not in use. Of course the connections from the rods 25 to the arm 37 will be such as to give the required degree of movement to the rods 25 of the two nozzles to give the desired results. When the nozzles are not in use 25 the piston 43 will be down at the bottom of the cylinder 41. When the piston 43 is thus forced by the spring 45 towards the end of the cylinder 41 which is shown as the lower end on the drawings the front end 28 of the 30 cleaning rod of the air nozzle 2 may project slightly outside of the latter; and then when the piston 43 is moved by the pressure of the air the rod 25 of the air cylinder 2 may be withdrawn approximately half an inch. 35 The distance which the cleaning rod 25 of the water nozzle 1 must move in order to open the water nozzle will then be about $\frac{1}{16}$ of an inch. The points of connection of the two rods 25 with the rocker arm 37 40 will be selected accordingly.

I have found that when a number of humidifiers as described above are utilized with the same source of air and water, the pressure at the nozzles of the humidifiers which 45 are farthest from the source of supply may drop somewhat; and consequently the humidifying effect of the various units may be uneven. A fall in the air pressure of any particular humidifier is not important, provided the amount of water available for consumption at each of the humidifiers is sufficient. Hence to secure efficient operation 50 of a humidifying system comprising a number of humidifiers means for directly controlling at each humidifier the action of the water nozzle 1 thereof must be provided.

55 For this purpose I utilize the structure shown in Fig. 6 wherein the cleaning rod 25 of the water nozzle 1 is connected with the rocker arm 37 by a link 40' in such a manner that the cleaning rod 25 is adjustable with respect to this link. The end of the link adjacent the outer end of the rod 25 has a fork 57, the stem of this fork being hollow 60 so that the link 40' can have its end bent

and passed through the stem and riveted over at the extremity as shown at 58. The outer extremity of the rod 25 is threaded as shown at 59 and on this threaded extremity between the two arms of the fork 57 is the round milled nut 60. The threaded end of the rod 25 passes through the fork 57 but the apertures in the two arms of this fork are not threaded. Hence by turning the nut 60 the rod 25 of the water nozzle 1 can be adjusted as desired. Each humidifier can thus be separately controlled and any drop in the air pressure for any particular air nozzle 2 can be compensated.

70 What is claimed is:—

1. A humidifier comprising a pair of nozzles, means for supplying water to one of said nozzles and air to the other, a cleaning element for each of said nozzles, a piston for actuating said elements, a housing for the piston exterior to the nozzles, means connecting the housing and the air nozzle, said piston being subject to the air flowing to the air nozzle to cause the cleaning elements to open both nozzles when the operation commences and means for moving the piston in the opposite direction to actuate the cleaning elements to close the nozzles when the operation ceases.

75 2. A humidifier comprising a mounting plate, a cylinder carried by the plate, a bracket adjustably secured to the plate, nozzles supported by the bracket, a pipe connected to said cylinder and one of said nozzles, a piston in the cylinder, a rod attached to the piston and projecting from the cylinder, a rocker arm journalled on one of said nozzles and connected to said rod, cleaning rods for the nozzles connected to said rocker arm, and a spring for actuating the piston, 100 the movement of said piston by said spring actuating the cleaning rods to prevent the nozzles from becoming obstructed, and the movement of the piston against the spring withdrawing said cleaning rods.

105 3. In combination with liquid and pressure fluid receiving nozzles having their discharge orifices contiguous to each other, a cleaning rod associated with the discharge orifice of each nozzle and movable relative thereto, a common means subject to the influence of the pressure fluid supplied to one of said nozzles and connected with said cleaning rods to simultaneously actuate said rods and withdraw the same from the nozzle orifices, and means acting upon said last named means when the pressure fluid supply is cut off to move said cleaning rods in the opposite direction and close the nozzle orifices.

110 4. In combination with liquid and pressure fluid receiving nozzles having their discharge orifices contiguous to each other, a cleaning rod associated with the discharge orifice of each nozzle and movable relative 115

thereto, a piston, means operatively connecting said piston with the cleaning rods, means for subjecting the piston to the influence of the pressure fluid supplied to one of the nozzles to move the piston in one direction and simultaneously withdraw the cleaning rods from the nozzle orifices, and a spring acting upon said piston to move the same in the opposite direction when the pressure fluid supply is cut off and simultaneously project the cleaning rods through the nozzle orifices to close the same.

In testimony that I claim the foregoing as my invention, I have signed my name hereto.

ALFRED M. GOODLOE.
